METHOD AND APPARATUS FOR FORMING TIES

Earl M. Famous, Upper Darby, Pa., assignor of fifty per cent to Harrison H. Heitmann, Glen-side, Pa.

Application April 5, 1939, Serial No. 266,051

7 Claims.

(Cl. 223—1)

This invention relates to the manufacture of neckware, and is concerned with a novel method and apparatus for forming ties.

In order to set out the objects and advantages of this invention, it is first necessary to outline a method now widely used in the commercial production of ties, as it is the primary object of this invention to obviate certain inconveniences and disadvantages associated therewith.

Such a method of producing so-called hand-made ties involves, first, the cutting of a piece of material into a required blank shape. It is now standardized practice in this art to cut the material on the bias, and, in order to make use of all available pieces, many of the tie blanks will comprise two or even three parts which are sewed together. After the blank has been cut it is given to the operator who has the duty of fashioning the same into tie form. In fashioning the tie a pair of cardboard forms are employed, there being one for the larger, full end of the tie, and a smaller one for the smaller end.

These cardboard forms are first laid out on the blank with the operator attempting to attain the correct position of the forms in relation to the blank by properly correlating the pointed ends of the form with respect to the points of the blank.

The lining for the ties is now laid over the forms and is also used as a guide in positioning the forms, after which the operator takes the blank and folds the same about the form, at the same time folding the edges at the joinder, which is to be the seam of the finished tie. As each part of the tie is folded, it is pinned so that it will be temporarily held in the formation attained. After being fashioned and held in its formed state by the pins, the seam of the tie is then sewed, the forms removed, and the tie passed onto the presser, the pressing operation being the last major step in the production of the tie.

The method of the character above-outlined presents many features of disadvantage and inconvenience. In the first place, there is inevitably variation in the size of the ties produced, this being attributed directly to the human factor involved in positioning the cardboard forms on the blanks. Due to the structural design of the ties, the forms are of a tapered construction; thus, if the form is too far up in the tie, the tie which is produced will be larger than when the form is farther out. Secondly, a certain amount of unevenness in the edges is also an almost inevitable result of this method of manufacture, due to the fact that the operator goes up the

form, folding over and pinning the portions thereof, it is impossible to pull each portion of the tie about the form with the same degree of tautness. Thus, certain portions of the tie blank are stretched to a greater degree about the form than are others. Thus, when the form is removed, those portions which have been stretched tight will constrict, leaving the uneven edges.

This same operation, involving the folding and stretching of the material about the forms also is intimately tied up with the formation of the seam. Therefore, if one side of the material is pulled around more at one place than the other, a crooked seam results, this being a highly undesirable factor in a tie intended for commercial disposition. Not only would the seams formed be crooked, but in many instances they would be off-center, thereby causing the points of the tie to be out of alignment with the seam. Ordinarily, the points of the tie should be in alignment with the seam.

As above pointed out, it is almost impossible for the operator to stretch the tie material about the form with the same degree of tautness therealong. When the form is removed, this results in a gathering in certain sections, and, perhaps, twisting in others. In forming the seam there is a tendency for the operator to turn under an uneven amount of the material along the seam. Thus, at one point of the seam there is too small an amount of the material turned under, while at other parts there is too much material turned under.

The above-noted disadvantages arise in addition to the time and trouble which is inevitably required of the operator who fashions the ties, the sewer, and the presser.

As above pointed out, the lining is employed as a guide in shaping the tie and in many instances, the lining is not true. The ties made with such imperfect linings often take the shape of the lining, with a poor product resulting.

When the blanks are made from two or more pieces, they are joined together. The joinder of the pieces provides extra thicknesses of material which must be accommodated in folding the edges of the seam, and great difficulty is experienced in getting the seam straight over these portions having the extra thickness of the material.

Many ties include a silk lining which extends partially up the inside of the larger or front end of the tie. In pressing this type of tie, the presser is very hard put to perform an operation which will not leave a line or impression that shows on

either side of the tie. Moreover, in pressing any type of tie, the presser usually employs a cardboard-press form and the pressing of the tie thereover usually leaves a small press mark when the forms are removed.

The above-noted features of disadvantage and inconvenience which are experienced in the forming of the usual, lined ties are multiplied many times when the manufacturer attempts to produce the so-called folded ties. These folded ties do not include linings, but merely comprise several layers of material which are provided by making the required number of folds in the blank. When a folded tie is perfectly produced, it is quite acceptable to the trade. However, the manufacturers have been unable to produce these folded ties in acceptable shape within the usual cost limits, the trouble, of course, residing, largely, in the difficulty experienced by the operator in getting the folds at the right place so as to provide a product having straight edges, an even seam, and with other undesirable factors eliminated.

With the foregoing in mind, this invention has in view, as its foremost objective, the provision of a method of forming ties in which the first step after the cutting of the blank is the pressing of the blank to form creases therein. These creases define the side edges of the tie as well as the folded edges at the seam.

A further object of the invention is the provision of apparatus for so creasing a tie blank and which apparatus includes means for insuring that the creases are properly located.

When a tie is made in accordance with the improved method of this invention, the creases constitute the guide for positioning the lining. Thus, any imperfections in the lining are not carried over into the tie. By employing apparatus that results in the proper positioning of the crease, absolute insurance that the ultimate tie will be of proper shape is given.

Moreover, by first pressing the blank, all press marks or impressions are entirely eliminated as there are no linings or forms contained in the tie after pressing to make such marks.

The new method involving the formation of the creases as the first step after production of the blank, permits the tie manufacturer to employ unskilled labor at all stages except for the sewing of the seam. Thus, the labor cost of the tie manufacturer is materially reduced; also, whether skilled or unskilled labor is employed, the actual time required in the production of a tie is materially reduced.

A method of tie manufacture which involves the formation of the creases as the first step after cutting of the blank is particularly adapted to the commercial production of folded ties as it substantially eliminates all the difficulties previously experienced in the production of these ties.

A further object of the invention is the provision of tie-forming apparatus of the character above-noted, which includes a bed carrying grooves which define the creases that are to be formed in the tie blank.

A more detailed object is the provision of such apparatus in which means for raising and lowering each end of the bed is included. When such means are employed, variation of the size of the tie may be obtained while still producing a tie substantially of the same shape.

Another object of the invention is the provision of apparatus which includes a top part movable with respect to the bed and which carries blades

that are complementary to the grooves in the bed. When the tie blank is laid over the bed, and the top moved so that the blades are inserted in the grooves, the blank is pressed with the blades and grooves forming the creases. Thus, as the operation is continued, each blank which is treated thereby will be creased in exactly the same manner, insuring uniformity in the size of the ties produced. By accurately locating the creases for the side edges and the edges for the folds in the seams, definite assurance is had that the seam of each tie will always be in the correct place.

Another object of the invention is the provision of apparatus of the character above-noted which includes means for supplying steam to the bed so that the blank will be properly pressed when treated thereon.

Another object of the invention is the provision of additional means for supplying steam at the bottom of the grooves at which the creases are formed. The latter means is preferably operable to supply the steam intermittently as occasion demands. When such apparatus is used, any likelihood of scorching the tie or causing a shine thereon is eliminated. By employing blades having a correct edge formation, any desired shape in the creases produced may be had. As a general rule, the rolled edge is more desirable in a tie. It is evident, therefore, that by employing blades having rounded edges a rolled crease is afforded. The definite assurance of the straight and even edges of the seam makes it easier for the sewer to run down the slip stitch, concealing the same well beneath the edge of the seam.

Another important advantage presented by the new method and apparatus of this invention is the substantial elimination of the use of any pins, which use so noticeably characterizes the prior art method above discussed.

A further object of the invention is the provision of apparatus of the character above-noted which includes guides for aiding in positioning a blank in the apparatus. These guides are preferably mounted in an adjustable manner so that different sized and shaped blanks may be accommodated.

Other details and advantages of the invention are associated with the mounting of the blades to render the same adjustable.

The invention, therefore, comprises a novel method of tie manufacture which includes, as a characteristic feature, the step of first pressing a tie blank to form creases therein immediately after production of the blank. An important part of the invention is apparatus provided for forming the creases above-noted.

For a full and more complete understanding of the invention, reference may be had to the following description and accompanying drawings, wherein:

Figure 1 is a perspective view of tie-forming apparatus made in accordance with the precepts of this invention,

Figure 2 is a top plan view of the apparatus shown in Figure 1, with the top opened up,

Figure 3 is a plan view of a tie blank prior to being creased by the apparatus of this invention,

Figure 4 is a view showing the tie blank after creasing,

Figure 5 is an enlarged detail view in perspective of a portion of the top, developing the manner of mounting the blades therein,

Figure 6 is a section through the apparatus with the top in closed position, and

Figure 7 is a section taken at right angles to the sectional showing of Figure 6.

Referring now to the drawings, wherein like reference characters denote corresponding parts, apparatus which is intended to be operable to crease tie blanks in accordance with the precepts of this invention is shown as comprising a bed referred to in its entirety by the reference character B and a top which is designated generally as T. The top T is movable with respect to the bed B, being preferably hinged thereto as shown at 10. The bed B may be carried by a supporting table shown at 11, which table is maintained in a convenient upraised location by legs 12.

Referring, for the moment, more particularly to Figure 6, the bed B is shown as including a steam chest 13, a supply line for admitting steam to the chest 13 being represented at 14 in Figure 1, and illustrated as including a control valve at 15. The steam chest 13 includes a top plate 16 on which rest a plurality of tie blank supporting and forming elements 17. The particular number, shape and relation of the forming elements 17 will vary with each machine, depending on the particular features of the tie which is intended to be produced thereby. It suffices to say that each of the forming elements 17 has an upper rounded or arcuate surface 18 which terminates at each side in an abrupt edge, as shown at 19. It is particularly notable that the edges 19 are spaced from the upper surfaces of the top plate 16, the members 17 being cut away therebeneath, as shown at 20.

The forming members 17 which are disposed at each side of the bed B, namely, those designated 17^a and 17^b, have the rounded surface and edge construction only along the inner sides thereof, this, because of the obvious fact that the tie blank is formed only over the inner portions.

Each of the members 17, 17^a and 17^b is fixedly secured at their centers to the top plate 16, as by the screw fastening element shown at 21 in Figure 7. However, each end of each of the members 17, 17^a and 17^b is movable with respect to the top plate 16 so as to assume the slightly bowed formation illustrated in Figure 7. To attain this result, the top plates 16 may be formed with notches 22 in which are seated the ends of screw members 23. The latter are threaded in openings 24 in the members 17, 17^a and 17^b, respectively.

By screwing the members 23 farther into the openings 24, the ends of the members 17, 17^a and 17^b will be raised from the top plate 16 while the ends may be lowered by reverse operation.

It will be noted that the edges 19 on the members 17, 17^a and 17^b, together with the rounded formation thereabove, define grooves, the bottoms of which are substantially at the edges 19. In order to supply steam intermittently to the bottom of the grooves, the top plate 16 is formed with lines of openings 25 immediately beneath the bottom of each groove. Enclosing the lower edges of the openings 25 are semi-cylindrical tubular members 26 which are secured to the underface of the top plate 16.

As shown in Figures 1 and 2, the several tubular members 26 may be connected by a manifold 27. A steam supply line for the manifold is shown at 28. Thus, steam may be supplied through the line 28 to the various members 26 entirely independently of the steam which is normally maintained in the chest 13.

The forming element 17^b, which is adjacent to the hinge connection 10, preferably carries a pair of guides such as shown at 29 and 30. These guides 29 and 30 are adjustably mounted by the set screws 31 as illustrated, and present inner edges 32 which are designed for engagement with a tie blank to aid in positioning the same.

The top T comprises a rectangular framework of substantially the same size and shape as the bed B and which is defined by side pieces 33 and ends 34. Located at appropriate points along the inner faces of the side pieces 33 are L-shaped slots 35, the bottoms of which are relatively elongated, as shown at 36. The L-shaped slots 35 on one side piece 33 are in corresponding positions with respect to the L-shaped slots 35 on the opposite side piece. The cross rods 37, preferably of the rectangular formation illustrated, are intended to be adjustably received in the elongated portions 36 of the L-shaped slots 35, suitable provision being made for holding the ends of the rods 37 in any adjusted position in the slots 36.

To provide this arrangement, the end of each rod 37 may be bifurcated, as shown at 38, and a tapered screw 39 threaded thereinto. When the screw 39 is threaded home, the bifurcated ends will spread to engage the top and bottom of the slots 36 to hold the end of the rod immovable therein. However, the screw 39 may be loosened to permit an adjustment of the end of the rod 37.

Just as many cross rods 37 may be employed as occasion demands. In the illustrated embodiment, four of these rods 37 are shown, although the number and relative positions of these rods can vary in accordance with the needs of any particular installation.

Carried by each rod 37 are a plurality of brackets 40 each of which has a U-shaped portion 41 which fits over the rod 37. A set screw, shown at 42, is carried by one leg of the U-shaped structure 41 and may be tightened to hold the bracket 40 in any adjusted position on the rod 37. Each of the brackets 40 has a depending leg 43 formed with a groove 44 which is intended to receive a crease-forming blade 45. A set screw shown at 46 is carried by the leg 43 at one side and may be tightened to hold the blade 45 in an adjusted position in the groove 44.

In reference to Figure 2 it will be noted that the blades 45 take the same form as the grooves defined by the edges 19 of the forming elements 17. The adjustment afforded by the slots 44 and wing nuts 46 permits of the blades being adjusted to any desired depth with respect to the grooves in the bed B. The adjustment afforded by the U-shaped structure 41 and set screw 42 permits of lateral movement of the brackets 40 along the rods 37 so that any desired curvature in the blades 45 may be obtained.

The operation of the above-described apparatus in forming ties will be described by first noting that the steam chest 13 of the bed B normally contains steam to keep the forming elements 17, 17^a and 17^b at a required temperature. Under ordinary conditions there is no steam supplied to the tubular members 26. After a blank has been cut (and if necessary, sewed), it is of substantially the formation shown in Figure 3, this blank being designated at 47.

The top T is now opened, the handle shown at 48 being availed of for this operation, and the blank 47 positioned on the bed, the guides 29 and 30 being availed of to insure of accurate positioning of the blank 47 over the forming elements 17, 17^a and 17^b. The top T is now swung

over into a closed position with the blades 45 entering the grooves in the bed. As they move downwardly in the grooves, the material of the blank 45 is indented and compressed and stretched over the rounded surfaces 18 of the forming elements 17, 17^a and 17^b which, it will be remembered, are heated by the steam chest 13.

After the top T is completely closed the operator admits steam to the feed line 28, to the manifold 27, and thence to the tubular members 26 so that the same is passed upwardly through the openings 25 to the material of the blank 47 at the bottom of the grooves. This heat, together with the engagement of the lower rounded edges of the blades 47, causes the formation of the creases shown at 49 in Figure 4. The top T may now be raised and the blank 47, with the creases 49 formed therein, and the material between the creases pressed, removed from the bed B. The creased blank may now be fashioned into a tie by the obvious steps required.

The swinging action of the top T as its moves toward the bed B is important because, with this particular type of movement, the blade 45, which is more closely adjacent to the hinge 10, is received in the groove between the forming elements 17^b and the next adjacent forming element 17 ahead of the reception of any of the other blades in the other grooves. As this first blade is moved downwardly in the groove, the material is stretched over the forming elements in an obvious manner, whereupon the next adjacent blade is received in its groove. Thus, the blades are forced into the grooves in sequential order rather than simultaneously, and this insures of a proper pressing of the blank.

While preferred specific embodiments of the invention are hereinbefore set forth, it is to be clearly understood that the invention is not to be limited to the exact constructions illustrated and described, because various modifications of these details may be provided in putting the invention into practice, within the purview of the appended claims.

I claim:

1. Apparatus of the character described comprising a bed, forming elements carried by the bed and having rounded surfaces and edges defining grooves, means for heating said bed, independent means for supplying steam to the bottom of said grooves, a steam supply for said independent means separate from said heating means and a blade assembly movable with respect to the bed and including blades adapted to be received in said grooves.

2. Apparatus of the character described comprising a bed, forming elements carried by the

bed, said forming elements being fixed at their central portions to the bed, means for adjusting the outer ends of said forming elements with respect to the bed, said forming elements having rounded edges and surfaces defining grooves, and a blade assembly movable with respect to the bed and having blades adapted to be received in said grooves.

3. In a tie-forming apparatus, a bed presenting grooves, an open top hinged to said bed, cross-pieces adjustably carried by the top, brackets carried by said cross-pieces, and blades carried by said brackets, said blades being adapted to be received in said grooves.

4. In a tie-forming apparatus, a bed presenting a plurality of grooves, a top hinged to said bed, cross rods adjustably mounted in said top, brackets adjustably carried by said cross rods, and blades adjustably carried by said brackets, said blades being adapted to be received in said grooves.

5. Apparatus for creasing a tie blank to form a plurality of tie-defining panels comprising a support, tie blank supporting and forming elements carried by said support and arranged to provide laterally spaced grooves, a blade assembly including blades arranged to smooth said tie blank over said forming elements and press portions of said tie blank into said grooves to form panel-defining creases, and means providing varying degrees of insertion of said blades into said grooves at different portions of the effective length of said grooves to alter the size and shape of said panels.

6. In the manufacture of ties, the method of forming diverging panel-defining creases in a tie blank for final folding and stitching which comprises indenting and compressing a tie blank to make a tie-forming crease, maintaining the material of said tie blank at said forming crease in a fixed position, then smoothing and tensioning said material away from said forming crease, and then making a second forming crease in said tie blank in laterally spaced and diverging relation to said first forming crease.

7. In the manufacture of ties, the method of preparing a tie blank for final folding and stitching which comprises indenting and compressing a tie blank to make a tie-forming crease, maintaining the material of said tie blank at said crease in a fixed position, then smoothing and tensioning a plurality of panels of said tie blank in progressive succession away from said forming crease, and indenting and compressing said tie blank intermediate said panels to provide additional forming creases.

EARL M. FAMOUS.
